UNITED STATES PATENT OFFICE.

ELIZABETH BASKERVILLE, OF NEW YORK, N. Y.; MARY S. BASKERVILLE ADMINISTRATRIX OF SAID ELIZABETH BASKERVILLE, DECEASED.

PETTICOAT.

Application filed January 26, 1924. Serial No. 688,808.

My invention relates to an improvement in petticoats.

The object is to provide a garment without fastenings, which will adjust itself to 5 the wearer's waist and preclude the possibility of becoming unfastened or dropping off the wearer.

Among other advantages, this petticoat through thorough test has proven to be 10 more comfortable than other petticoats, especially for wear under full skirts, or any of the new wrap-around models. Being made on the wrap-around plan, it allows any 15 length of step or movement giving perfect freedom to the legs, which is especially advantageous for sportswear and dancing. In taking a long stride, the panel opens with the stretch of the legs and the movement of of the legs is thus unhampered and when the 20 stride ends the folds fall back into place without any binding bunchiness or usual clumsiness. At the same time there is no extra fullness at the waistline, or anywhere else to make the outer garments appear 25 lumpy. This petticoat may be worn with either a narrow skirt or a full-pleated one with an equal amount of comfort. It also has the advantage of the double back, giving the shadow-proof effect now greatly 30 de- sired in articles of this character. Hence, in a petticoat seemingly no fuller or wider than the usual tailored styles, ample room is allowed for the most energetic sports and 35 dancing. Furthermore, the panel never opens to such an extent that the limbs are exposed to view.

In the accompanying drawings:

Figure 1 is a view in perspective;

Figure 2 is a rear view of the skirt; and

40 Figure 3 is a fragmentary view, showing the construction at the waistline.

While the petticoat 1 is of the wrap-around type in which there is about a one-third overlap at the back forming a shadow-proof garment, nevertheless in the preferred 45 construction it is fashioned at the top into a single continuous hem 2 better illustrated in Figure 3, and through this hem a single continuous elastic band 3 extends, its ends being 50 permanently secured together as would appear from Figure 2, thus doing away entirely with snaps, hooks or buttons which are continually coming off or getting out of order, and which have to be placed at a pre- 55 determined point to suit the waistline of the wearer, whereas in the present invention the

elastic band 3 is of a size to adjust the waistline of the petticoat to the waist of the wearer, yielding however with every motion of the body while precluding the possibility of becoming unfastened with the attendant danger of dropping or losing the petticoat which not infrequently happens.

The portion doubled over at the back simply gives a double fold or layer throughout about one-half, namely the back, of the circumference of the petticoat and corresponding double layer or ply at the hem as shown at 2 in Figure 3.

The petticoat thus formed not only 70 spreads at the bottom to give perfect freedom to the legs, but also is little less yielding at the waist which it embraces with sufficient tension to always keep it in place and yet with a sufficient degree of elasticity to 75 permit it to yield to pressure, strain and every motion of the abdomen, and in fact the whole body. No other petticoat does this. It would be impossible with a wrap-around petticoat brought together and held with 80 snaps, hooks and eyes or buttons.

To give a finish to the edges, they may be 85 trimmed with net or lace, etc. 4 as shown, although this is of course of secondary importance.

A petticoat of this type has the further 90 advantage of being easily laundered and always holds its shape and lends itself readily to the motions of the body, and particularly to the legs.

I claim:

1. A garment of the wrap-around type having its ends overlapped throughout a portion of its width forming a shadow-proof garment, the upper edges of the overlapped and underlapped portions being together folded over to form a single, continuous, closed hem encircling the garment, and an elastic band enclosed in said hem.

2. A garment of the wrap-around type 100 having its ends overlapped throughout a portion of its width forming a shadow-proof garment, the upper edges of the overlapped and remaining portion folded over into a single continuous hem encircling the upper 105 edge of the garment the material forming said hem being double throughout the overlapped portion of the garment, and a permanently closed elastic band held in said hem.

In testimony whereof I affix my signature.

ELIZABETH BASKERVILLE.
